UNITED STATES PATENT OFFICE.

HERBERT HENRY BERRY AND JAMES WATT REID, OF LONDON, ENGLAND.

ELECTRIC FIRE.

1,349,804.

Specification of Letters Patent. Patented Aug. 17, 1920.

Application filed December 30, 1919. Serial No. 348,368.

To all whom it may concern:

Be it known that we, HERBERT HENRY BERRY and JAMES WATT REID, both citizens of the United Kingdom of Great Britain and Ireland, and both residents of 86 Newman street, London, W. 1, England, have invented certain new and useful Improvements in Electric Fires, of which the following is a specification, such as will enable others skilled in the art to which it appertains to make use of the same.

This invention relates to electric fires of that kind in which one or more electric lamps is or are arranged inside a guard or equivalent, the front and top of which is covered with imitation fuel, and inside which rotatable devices are turned by heat from the lamp or lamps and produce a flickering effect.

20 In accordance with the present invention the fans are mounted on the top of the guard which is movable and are lifted with it when it is raised so that easy access may be had to the lamps and fans.

25 The movable top may, as has been heretofore proposed, be hinged to the body portion of the guard or it may be capable of being raised or lifted upward away from the body portion. The necessity of removing 30 the imitation fuel, lifting out the guard, etc., when access is desired to the lamps and fans is thus obviated.

The invention is illustrated on the accompanying drawings in which:—

35 Figure 1 shows an ordinary fireplace *a* in front elevation.

Fig. 2 is a cross sectional view about the line 2—2 of Fig. 1, and

Fig. 3 shows the guard and some of the fuel removed.

40 Fig. 4 shows a modification.

Referring to Figs. 1, 2 and 3, the guard *b* is simply placed within the fireplace and over the lamps *c* and is covered on the front and top with either or both fixed and loose 45 "fuel" *d*. The top *f* of the guard is hinged to the bottom portion and has on its underside two fans *e* supported by bars *g* and the top in such a manner that, as is clearly 50 shown in Fig. 3 the top can be raised and the lamps and fans easily handled.

55 In Fig. 4 the guard *h* is provided with a top *i* which is entirely removable and is furnished with feet *j* adapted to fit into loops *k* in the guard.

What we claim and desire to secure by Letters Patent is:—

In an electric imitation fire, a basket to contain electric lamps, a movable top for the basket, imitation fuel on said top, and fans 60 arranged under the top and connected thereto for rotation, said fans being carried wholly by and removable with said top.

In testimony whereof we have affixed our signatures in presence of two witnesses.

HERBERT HENRY BERRY.
JAMES WATT REID.
